UNITED STATES PATENT OFFICE

156,797

LACE

William H. Woodhouse, Mount Vernon, N. Y., assignor to Acme Laces, Inc., New York, N. Y., a corporation of New York

Application January 27, 1949, Serial No. 532

Term of patent 3½ years

(Cl. D47—6)

To all whom it may concern:

Be it known that I, William H. Woodhouse, a citizen of the United States of America, residing in Mount Vernon, county of Westchester, and State of New York, have invented a new, original, and ornamental Design for a Lace, of which the following is a specification, reference being had to the accompanying drawing, forming part thereof.

The figure is a plan view of a lace showing my new design.

The broken lines on the drawing outline a design unit which unit is repeated throughout the length of the lace.

I claim:

The ornamental design for a lace, as shown and described.

WILLIAM H. WOODHOUSE.
